SHOCK RESISTANT SPARK PLUG

Merton D. Haworth, Fanwood, N. J., assignor, by
mesne assignments, to the United States of
America

Application November 12, 1952, Serial No. 319,807

5 Claims. (Cl. 317—83)

1

The invention relates generally to spark plugs and particularly to those which are subjected to a substantial amount of shock due to impact, vibration or other factors. In certain devices which employ spark plugs that are subjected to a substantial amount of shock, the problem of failure of the spark plugs due to fracturing of the porcelain insulator is very real. A specific example of a device of this type is the mechanized, military flame thrower. The mechanized flame thrower is mounted on a tank or other military vehicle, and under field conditions of use is subjected to shock due to the impact of ammunition on any part of the tank or vehicle, and to road shock. The flame throwers include an igniter spark plug in their ignition chamber which ignites the flame producing material. Failure of the spark plug incapacitates the entire flame thrower and consequently constitutes a serious problem.

It is an object of this invention to provide a spark plug which is satisfactorily shock resistant to the conditions existing in the field use of mechanized, military flame throwers and in other devices subjected to substantial shock.

It is another object of this invention to provide a shock resistant spark plug which may be used interchangeably with conventional spark plugs and therefore precludes the necessity for any change or adaptation in existing equipment in converting from the old to the new plugs.

It is a specific object of this invention to provide a resiliently mounted, shock resistant, spark plug for a mechanized, military, flame thrower which can withstand the ballistic and road shock of the vehicle carrying the flame thrower operating under field conditions.

It is a further object of this invention to provide a shock resistant spark plug which is made of non-corrosive materials; substantially unaffected by temperature and humidity variations; suitable for mass production; easily installed and maintained; and which satisfies the electrical requirements of a high tension, ignition circuit.

These and other objects will become apparent from the following description and claims taken in conjunction with the drawings wherein:

Fig. 1 is a longitudinal, sectional view of the forward portion of a flame thrower barrel.

Fig. 2 is a front, elevational view of the flame thrower barrel shown in Fig. 1.

Fig. 3 is a sectional view taken on line 3—3 of Fig. 4.

Fig. 4 is a sectional view taken on line 4—4 of Fig. 3.

2

Fig. 1 shows the forward portion of a flame thrower barrel and particularly shows the structure which constitutes the ignition chamber. The ignition chamber designated generally by reference numeral 10 is the part of the flame thrower where the flame producing material and the igniting material contact each other, and are ignited by sparks caused by one or more igniting spark plugs. This invention relates primarily to the spark plugs 12 which create the sparks which ignite the materials in the ignition chamber.

The ignition chamber 10 is formed by the forward portion of cylindrical flame thrower barrel 14 and the ignition chamber wall 16, which is positioned within and secured to said barrel. Wall 16 has a central opening 18 formed therein which receives the flame producing material barrel 20 and maintains it concentrically within and spaced from the flame thrower barrel 14. As can be seen in Fig. 1, the forward end of barrel 20 is beveled at 22 to facilitate ejection of the flame producing material out of said barrel. The rearward end of barrel 20 communicates with a conventional source of flame producing material (not shown). Ignition chamber wall 16 has two threaded openings 24 and 26 formed therein, each of which is adapted to receive the externally threaded collar of a spark plug. Wall 16 has two additional openings which receive and position igniting material nozzles 28 and 30, which are in communication through appropriate piping with a source of igniting material (not shown). The relative positions of the spark plugs and nozzles in the ignition chamber wall 16 can be best seen in Fig. 2. Flame thrower barrel 14 has air vents 32 and 34 formed therein, and at its forward end it supports fixed, grounded electrodes 36 and 38.

All of the structure described above is substantially conventional flame thrower structure and constitutes the prior art setting for the prior art spark plugs. Very briefly, the prior art spark plugs comprise a central electrode which is surrounded by a long, cylindrical, porcelain insulator having an integral flange formed thereon which is adapted to be surrounded by a crimped metal collar. This collar is externally threaded on one side of its ends and is adapted to be rigidly attached to the wall 16 in one of the openings 24 and 26.

As was previously stated, the prior art arrangement was defective in that the rigid attachment of the spark plug to the ignition chamber wall 16 permitted ballistic, road and other shocks to be transmitted through the flame thrower-bar-

rel, ignition chamber wall, and spark plug collar to the porcelain insulators. In a large number of cases this caused fracturing of the insulators and resulted in the spark plugs failing, thereby incapacitating the entire flame thrower. My invention resides in providing a novel spark plug which eliminates this serious defect.

Referring particularly to Figs. 3 and 4, the improved spark plug comprises conventional Nichrome wire electrode 40 which is adjustably mounted in porcelain insulator 42. Threaded end 43 of electrode 40 is adjustably received within threaded opening 44 formed in insulator 42, and is adapted to contact the terminal end 48 of electrical current conductor 50. Terminal end 48 is positioned in connector 46 which is secured to threaded end 43 and appropriately insulated as by insulating jacket 52. Electrode 40 may be adjusted to vary the amount thereof which projects out of the insulator 42 to thereby vary the distance between itself and its associated, grounded electrode, and can be locked in any adjusted position by lock nut 54 which is made of an insulating material. Porcelain insulator 42 has a centrally located flange 56 formed thereon which is adapted to be surrounded by soft steel collar 58 which may be crimped thereon or molded thereabout. Externally threaded mounting nut 60 is positioned concentrically about and spaced from insulator 42. As can be clearly seen from Fig. 3, mounting nut 60 has an aperture 62 which has an internal diameter in excess of the external diameter of insulator 42 which thereby provides an annular space between the insulator and the mounting nut. Collar 58 is connected to nut 60 by three flexible spring fingers 64. Each spring finger 64 is electrically spot welded to the collar 58 and the nut 60 at points 66 and 68 respectively (see Fig. 3). Electrical spot welding makes it possible to effect an adequate joint between the flexible spring fingers and the parts to which they are secured without destroying the resilience of said spring fingers.

As can be seen in Figs. 1 and 2, the spark plugs 12 are mounted in the openings 24 and 26 in the ignition chamber wall 16. The flexible connection between the electrode and insulator carrying collar 58 and the mounting nut 60 of each spark plug substantially prevents any shock which might be imparted to the flame thrower from being transmitted to the insulator 42. In this regard it should be noted that insulator 42 is free to move within aperture 62 relative to nut 60.

The events which transpire in the ignition chamber 10 are the following: A flame producing material such as a jellied gasoline is ejected out of the barrel 20 into the ignition chamber 10 by actuation of the appropriate trigger on the flame thrower. An igniting mixture of gases is sprayed out of the nozzles 28 and 30 into the ignition

chamber 10 simultaneously. By actuation of another trigger, a spark is caused between the tip of the electrode 40 of each of the spark plugs 12 and their respective, associated, grounded electrodes 36 or 38. The sparks ignite the gas mixture which in turn ignites the jellied gasoline.

Having described one specific embodiment of my invention, I do not thereby intend to limit myself to the precise arrangement disclosed but intend to include all equivalent structure which falls within the spirit of the invention and the scope of the appended claims.

I claim:

1. In a mechanized military flame thrower having a main barrel, a wall secured in said barrel thereby establishing an open ended ignition chamber, means for introducing a flame-producing material into said ignition chamber, means for introducing an igniting material into said ignition chamber, and means for causing a spark in said ignition chamber, the improvement in said means for causing a spark comprising a resiliently mounted spark plug.
2. A device as defined in claim 1 wherein said spark plug includes an electrode, an insulating jacket surrounding said electrode, a collar surrounding said jacket, a nut adapted to be secured in said wall, and a flexible finger connecting said collar and said nut.
3. A device as defined in claim 2 wherein said nut is apertured, and is positioned concentrically about and spaced from said jacket.

4. A shock resistant spark plug comprising, an externally threaded metallic mounting nut having a longitudinal internal aperture, an elongated insulator extending through said aperture and beyond said nut, the exterior diameter of the portion of said insulator lying within said aperture being substantially less than the diameter of said aperture, said insulator being formed with an integral flange exterior of and spaced from said nut, a metallic collar formed about said flange and having an external dimension substantially the same as an external dimension of said nut, a plurality of narrow, elongated spring strips joining said collar with said nut at points of equal dimension, and an electrode extending longitudinally through said insulator.

5. A spark plug as defined in claim 4 wherein said nut and said collar are formed with a plurality of flat exterior surfaces and wherein said spring strips are flat and spot welded to said flat exterior surfaces.
